UNITED STATES PATENT OFFICE

LOUIS P. MONTANEY, OF WENATCHEE, WASHINGTON

PNEUMATIC DISPLACEMENT PUMP

Application filed October 9, 1926. Serial No. 140,440.

This invention relates generally to pneumatic displacement pumps and more particularly to improvements in fluid pressure actuated valves for automatically controlling the operations of said pumps.

Contemplated by the invention is the provision of a pneumatic displacement pump of the submerged type, embodying means whereby the same is automatically and positively maintained in a normally submerged condition, and embodying a fluid pressure actuated valve, for automatically and positively controlling the normal operations of the pump, having a series of inlet and exhaust ports provided with spring-pressed air sealing devices, which function to positively and effectually prevent passage of fluid pressure between said ports and which also function and serve to automatically take up any wear occurring in the valve while in use, all of which are important objects of the invention and are to be correlated in the broad aim of enhancing the efficiency of the pump for general use.

The above, and additional objects which will hereinafter be more specifically treated are attained by such means as are shown in the accompanying drawings, described in the following specification and then more clearly pointed out in the claims, which are appended hereto and form part of this application.

With reference to the drawings, in which there is illustrated one embodiment of the invention, and throughout the several views of which like characters of reference designate similar parts.

Figure 1 is a vertical medial section of a pneumatic displacement pump fabricated in accordance with the invention, certain parts thereof being in elevation and certain other parts being omitted for clarity of illustration.

Fig. 2 is an enlarged vertical medial section of the pump control valve.

Fig. 3 is a vertical section of the same taken through 3-3 of Fig. 2.

Fig. 4 is a horizontal section taken through 4-4 of Fig. 2, and

Fig. 5 is an enlarged vertical medial section of a spring-pressed air sealing device employed with the pump control valve, especial-

ly designed to take up wear therein, as it would appear when removed therefrom.

Beginning the more detailed description of the invention by reference to the drawings, the numerals 10 and 11, respectively, designate pump cylinders or chambers closed at their lower ends by a common bottom cover or plate 12, and at their upper ends by a common top cover or plate 13 rigidly secured to or upon the ends of said pump cylinders in any well known or suitable manner.

Provided within the bottom cover 12 and leading to the pump cylinders 10 and 11 are inlet openings 14 controlled by foot valves 15. Connected to said bottom cover 12 and communicating with said pump cylinders are outlet or discharge pipes 16 having check valves 17 interposed therein, said outlet pipes being interconnected above and adjacent said check valves to a common discharge pipe or rising main 18 leading and connected to a water delivery system, not shown. It has been found particularly advantageous and desirable in practice and after exhaustive experimentation to interpose within the discharge pipe 18, at a point preferably above the pump cylinders, a ball or float valve 19, of any suitable type, actuated by the water in the well, or other service of supply, for effectually controlling the level of such water and for positively preventing the same from falling below the tops of the pump cylinders, inasmuch, as the pump functions more efficiently when the cylinders are completely submerged at all times, than when the same are not. In this connection it may be well to state, that when the water falls below the predetermined or selected level, it will be evident and apparent that the valve 19 will close and that the column of water in the discharge pipe 18 in conjunction with the float of said valve will serve and function at such times to retain and maintain the valve in a closed position against the action of the pneumatic pressure in either of the pump cylinders tending to open the same. Obviously, therefore, closing of the valve 19 automatically stops the pump and no water may be withdrawn through the discharge pipe 18 from the well or other source of supply until the level of

the water therein again rises above the predetermined minimum low point, in order that the pump may function efficiently and effectively.

5. Provided within the top cover 13, in concentric relation to the pump cylinders 10 and 11, are fluid pressure outlet openings or ports 20 controlled by float actuated rubber-faced conical valves 21 seatable within the lower 10 ends thereof and enclosed by cylindrical caps or casings 22 mounted within or upon the inner face of said top cover 13, said caps having the cylindrical walls adjacent the lower ends thereof perforated, whereby communication is established between the openings 20 and the pump cylinders 10 and 11 when the valves 21 are unseated, as will be readily apparent by referring to Fig. 1. Rigidly secured to the valves 21 are dependent stems or 15 rods 23 guided at their upper ends for limited axial movement within the caps 22 and at their lower terminals are provided with cylindrical floats or buoyant casings 24 actuated by the incoming and outgoing water to seat 20 and unseat the valves 21, which latter when unseated function as stops and abut the end walls of their correlated caps 22, as shown more clearly in Fig. 1, to thereby positively limit their travel or downward movements.
25. Connected to the top cover 13 and communicating with the pump cylinders 10 and 11 are fluid pressure delivery pipes 25 and fluid pressure exhaust or return pipes 26 closed, when the water level in the pump cylinders reach the tops thereof, by floats 27 slidably mounted upon dependent stems 28 rigidly secured at their upper terminals within the said top cover 13. Connected to and communicating with the openings 20 are auxiliary fluid pressure exhaust pipes 29.
30. The numeral 30 designates a pump control valve casing or housing having fluid pressure supply ports 31, wherewith the delivery pipes 25 are connected, and having fluid pressure exhaust ports 32, wherewith the exhaust pipes 26 are connected, while the auxiliary exhaust pipes 29 are connected to and communicate with the ends of said casing. Snugly seating for reciprocative movement within the casing 30 is a slide valve 33, having a central fluid pressure inlet port 34 for alternate registration with the supply ports 31 thereof, and having fluid pressure exhaust ports 35 for alternate registration with the exhaust ports 32 of the same. The slide valve 33 is positively secured within the valve casing 30 against unseating or dislodgment therefrom by a cover 36 rigidly secured thereto by stud bolts or cap screws 37. The cover 36 is provided with fluid pressure inlet ports 38 disposed in axially aligned relation with the supply ports 31 of the casing 30 for alternate registration with the inlet port 34 of the slide valve 33, and is also provided with fluid pressure exhaust ports 39 disposed

in axially aligned relation with the exhaust ports 32 of said casing 30 for alternate registration with the exhaust ports 35 of said slide valve 33. Connected to and communicating with the inlet ports 38 of the valve cover 36 are branched fluid pressure supply pipes 40 leading from a common and suitable source of fluid pressure, not shown.

Formed within the valve abutting face of the casing 30 in concentric relation to the supply and exhaust ports 31 and 32 thereof and within the valve abutting face of the cover 36 in similar relation to the inlet ports 38 thereof are annular recesses or channels 41, wherein spring-pressed sealing rings 42 are slidably seated having their inner terminal portions 43 exteriorly reduced for the reception of cup leathers 44 and cup leather retention washers or collars 45, which latter are rigidly secured to the sealing rings 42 by crimping or riveting the ends of the portions 43 thereon, to thereby provide unitary air sealing structures of the type more clearly disclosed in Fig. 5. Interposed between such unitary air sealing structures and the inner ends of the annular recesses 41 are helical springs 46 for maintaining the sealing rings 42 in proper contact with the lower and upper faces of the slide valve 33 to thus positively and effectually prevent passage of fluid pressure between said valve and the contiguous faces of the casing 30 and cover 36, while also serving and functioning to automatically take up wear between said slide valve and said faces. Actual experience has demonstrated the primary importance of properly lubricating the unitary air sealing structures to materially lessen any tendency of the same sticking within their correlated annular recesses 40 and to maintain the cup leathers of such structures in a soft pliable condition whereby their air sealing qualities and properties are materially enhanced, this is accomplished by partially filling the annular recesses 41 with a suitable grease prior to the insertion therein of the unitary air sealing structures during the initial assembling of the pump control valve or when said valve is being overhauled.

Integrally formed within the valve casing 30 upon the end walls thereof are inwardly projecting abutment bosses 47, with which the ends of the slide valve 33 alternately abut during reciprocative movements of the same, and when in abutment with said bosses said valve ends are spaced from the end walls of the casing 30, in the manner shown at the left in Figs. 2 and 4, to thereby permit and positively insure of the exhaust fluid pressure from the auxiliary exhaust pipes 29 impinging uniformly and alternately upon the entire area of each of said valve ends to effect reciprocation of the slide valve.

To prevent reciprocation of the slide valve 33 when the pump is inactive, air bleeding or

exhausting conduits 48 are connected to and communicate with the ends of the valve casing 30, whereby any fluid pressure which may become trapped in said ends for any reason 5 is exhausted therefrom through said conduits to the atmosphere.

To obtain the best and most efficient results from the pump herein shown and described, such pump must be completely submerged at 10 all times, substantially in the manner disclosed in Fig. 1, so that during the operation of the same, the pump cylinders 10 and 11 may be completely and rapidly filled, the floats 24 elevated to seat the valves 21, the 15 floats 27 elevated to close the pipes 25 and 26, and the ball valve 19 maintained in an open position to provide a free and unobstructed passage through the discharge pipe 18. The pump will operate at any depth 20 under water, but, unnecessary submergence will increase the lift of the pump without any corresponding advantage accruing therefrom. In this connection it may be well to state that, while the pump is completely and 25 normally submerged, the control valve thereof may be located at the top of the well or at any other convenient point, where it is readily accessible for inspection, overhauling, 30 repairs or replacement.

In practical operation the pump is operated by fluid pressure such as compressed air, which holds the water under pressure at all times, either in the pump cylinder 10 or the pump cylinder 11, depending upon the position 35 of the slide valve 33, as, for example, assuming that the several mechanisms of the pump are disposed in the positions illustrated in Figs. 1 to 4 inclusive, wherein it will be observed that the valve 21 of the pump cylinder 10 has been seated by its float 24, and the 40 delivery and exhaust pipes 25 and 26 of said pump cylinder have been closed by their float 27, while the valve 21 of the pump cylinder 11 has been unseated by its float 24 to 45 admit exhaust fluid pressure therefrom to the end of the valve casing 30 connected therewith, whereby the slide valve 33 has been actuated and moved to the position as shown, to register the inlet port 34 of said slide 50 valve with the valve casing supply port 31 and the valve cover inlet port 38 of the pump cylinder 10, so that the water contained therein was directly subjected to and instantly brought under air pressure and the foot valve 55 15 thereof positively closed, as shown. With the slide valve 33 in the position shown and described, the valve exhaust port 35, provided for the pump cylinder 11, registers with the valve casing exhaust port 32 and the valve 60 cover exhaust port 39, of said pump cylinder, as more clearly shown in Fig. 3, whereby fluid pressure previously contained in the pump cylinder is exhausted therefrom and water is caused to flow thereinto through the 65 inlet opening 14 thereof, the foot valve 15

controlling said opening being elevated by the water flowing therethrough. As the water flows into the pump cylinder 11 the float 24 therein will be elevated to seat its valve 21 and such water will continue to flow 70 into said cylinder until the same is filled, whereat the float 27 thereof will be elevated to close the delivery and exhaust pipes 25 and 26 associated therewith, to thus prevent any gritty or foreign matter, which may be 75 carried in suspension by said water from entering said pipes, where it is likely to reach and find lodgement in the pump control valve, causing damage thereto and materially lessening the life of the same. 80

When no water is drawn off or used, the pump is inactive and the several mechanisms thereof may remain in the positions illustrated, in the several views, indefinitely, with the exception that the pump cylinder 11 will 85 fill with water causing elevation of the float 24 with the consequent seating of its valve 21 and causing elevation of the float 27 to close its delivery and exhaust pipes 25 and 26, as hereinbefore described. However, 90 when a faucet or valve, of the water delivery system, not shown, is opened, the air pressure in the delivery pipe 25 connected with the pump cylinder 10 unseats the float 27 and forces the water stored therein downwardly 95 and outwardly therefrom through the outlet pipe 16 and thence upwardly through its check valve 17 and the common rising main 18. Upon closing of the faucet or valve, the pump will again be rendered inactive, and 100 if the amount of water withdrawn, while the faucet was open, was insufficient to empty the cylinder 10, the water remaining therein will be held under air pressure, so that when the faucet is again opened such air pressure 105 will force the water remaining in said cylinder outwardly therefrom through the outlet pipe 16 and rising main 18. As the level of the water in the cylinder 10 nears the lower end thereof the float 24 in said cylinder descends and unseats its valve 21, whereupon fluid pressure from the cylinder 10 is 110 admitted to the end of the valve casing 30 connected therewith, to directly and uniformly impinge thereat upon the adjacent end 115 wall of the slide valve 33 and move the latter to the opposite end of said casing to register the valve exhaust port 35, provided for the pump cylinder 10, with the valve casing port 32 and the valve cover port 39 of 120 said pump cylinder, so that the fluid pressure therein is exhausted therefrom and water will flow thereinto through its inlet opening 14 following the elevating by the incoming water of the foot valve 15 controlling said opening. Simultaneously with the foregoing the exhaust ports of the pump cylinder 11 are closed and the inlet port 34 of the slide valve 33 registers with the valve casing supply port 31 and the valve cover inlet port 38 of said 130

pump cylinder, whereupon the air pressure in the delivery pipe 25 unseats the float valve 27 of the cylinder and seats the foot valve 15 thereof, so that the water stored in the cylinder is forced downwardly and outwardly through its outlet pipe 16 and thence upwardly through its check valve 17 and the common rising main 18 to the point of discharge. While water is being drawn off or used the valves 21 of the pump cylinders 10 and 11 are alternately seated and unseated by their correlated floats 24, to thereby reciprocate the slide valve 33, as hereinbefore set forth, and upon the closing of the faucet or other discharge opening of the water delivery system, the pump will again be rendered inactive.

When the pump is operating under normal working pressure complete reciprocative movements are positively imparted thereby to the slide valve 33 and any tendency of such valve to stick in an intermediate position is eliminated or minimized. Actual experience has shown that if the fluid pressure is sufficient to raise the water ten feet or more, such pressure will completely throw or move the slide valve 33 its full travel in either direction and will positively prevent rebounding of the same at the ends of its travel. However, if for any reason the slide valve 33 should become stuck in an intermediate or dead center position, as for example, should such slide valve take a position to simultaneously close both the inlet and exhaust ports and thus become stalled, then and in that event fluid pressure is injected into the valve casing 30 through one of the bleeder pipes 48, to thereby move the slide valve 33 to the end of its travel whereafter such valve will function in a normal manner.

Manifestly, therefore, it is a primary purpose and aim of the invention to provide a control valve for a pneumatic displacement pump, that is extremely simple, durable and economical in construction, that is positive, efficient and reliable in use and operation, that is readily and conveniently accessible, that will not readily get out of order, and that embodies air sealing devices for the several ports thereof, which function to positively and effectually prevent passage of fluid pressure therebetween and to take up any wear in said valve.

While I have herein disclosed my invention with sufficient detail to enable those skilled in the art to understand the mode of construction, and the principles involved, it is to be understood, that there is no intentional limitation herein to the specific form and precise details of construction of the invention shown and described, except as expressly defined by the appended claims, and that various modifications of such form and construction may be resorted to without departing from the spirit of the invention or

the benefits derivable therefrom. I also desire to have it understood that certain features of the invention herein disclosed, may be employed in other combinations than those shown and described. 70

What I claim as my invention, and desire to secure by Letters Patent, is:—

1. The combination with a pneumatic displacement pump control valve, of means for simultaneously bleeding both ends of said valve when its correlated pump is inactive, said bleeding means being normally open to the atmosphere. 75

2. The combination with a pneumatic displacement pump control valve, of means for simultaneously bleeding to the atmosphere air leakages from both ends of said valve during idle periods of its correlated pump, said bleeding means being normally open to the atmosphere. 80

3. The combination with a pneumatic displacement pump control valve, of means for throwing valve over in the event the same became stalled in an intermediate position. 85

4. The combination with a pneumatic displacement pump control valve, of means for injecting fluid pressure into the valve casing for moving the valve to the end of its travel in the event the latter became stalled in an intermediate position. 90

5. The combination in a pneumatic displacement pump having a valve controlled fluid pressure port, of a fluid pressure sealing device for said port disposed in concentric relation thereto for abutment with the valve controlling said port, and adapted to be positively maintained in abutment with said valve by the fluid pressure. 100

6. The combination in a pneumatic displacement pump having a valve controlled fluid pressure port, of a spring-pressed fluid pressure sealing device for said port, disposed in concentric relation thereto for abutment with the valve controlling said port, and adapted to be positively maintained in abutment with said valve conjointly by its correlated spring and the fluid pressure. 105

7. The combination in a pneumatic displacement pump having valve controlled fluid pressure ports, of spring-pressed fluid pressure sealing devices individual to said ports and disposed substantially in concentric relation thereto for abutment with the valve controlling the ports, said devices being adapted to be positively maintained in abutment with said valve conjointly by their correlated spring and the fluid pressure. 115

8. The combination in a pneumatic displacement pump having a valve controlled fluid pressure port provided with an annular recess concentrically disposed in spaced relation thereto, of a fluid pressure sealing device seated within said recess for abutment with the valve controlling said port and adapted to be positively maintained in abut. 125

ment with said valve by the fluid pressure.

9. The combination in a pneumatic displacement pump having a valve controlled fluid pressure port provided with an annular recess concentrically disposed in spaced relation thereto, of a spring-pressed sealing device seated within said recess for abutment with the valve controlling said port and adapted to be positively maintained in abutment with said valve conjointly by its correlated spring and the fluid pressure.

10. The combination in a pneumatic displacement pump control valve having a fluid pressure port, of a fluid pressure sealing device for said port disposed in concentric relation thereto for abutment with a complementary sealing face, and adapted to be positively maintained in abutment with said face by the fluid pressure.

11. The combination in a pneumatic displacement pump having a valve controlled fluid pressure port provided with an annular recess concentrically disposed in spaced relation thereto, of a spring-pressed fluid pressure sealing ring slidably seated within said recess for abutment with the valve controlling said port and adapted to be positively maintained in abutment with said valve conjointly by its correlated spring and the fluid pressure.

12. The combination in a pneumatic displacement pump, of a valve casing having inlet and exhaust fluid pressure ports formed therein provided with annular recesses concentrically disposed in spaced relation thereto, a slide valve mounted within said casing having inlet and exhaust fluid pressure ports for alternate registration with the ports of said casing, and spring-pressed fluid pressure sealing rings seated within said annular recesses for abutment with said valve and adapted to be positively maintained in abutment therewith conjointly by their correlated springs and the fluid pressure.

13. The combination in a pneumatic displacement pump, of a valve casing having inlet and exhaust fluid pressure ports formed therein provided with annular recesses concentrically disposed in spaced relation thereto, a fluid pressure actuated valve mounted within said casing having inlet and exhaust fluid pressure ports for alternate registration with the ports of said casing, and spring-pressed fluid pressure sealing rings seated within said annular recesses for abutment with said valve and adapted to be positively maintained in abutment therewith conjointly by their correlated springs and the fluid pressure.

14. The combination in a pneumatic displacement pump having a valve controlled fluid pressure port provided with an annular recess concentrically disposed in spaced relation thereto, of a fluid pressure sealing ring seated within said recess for abutment with

the valve controlling said port and a cup leather secured to said sealing ring whereby the fluid pressure is utilized to positively maintain the sealing ring in abutment with said valve.

15. The combination in a pneumatic displacement pump having a valve controlled fluid pressure port provided with an annular recess concentrically disposed in spaced relation thereto, of a fluid pressure sealing ring seated within said recess for abutment with the valve controlling said port, a compression spring for said sealing ring, and a cup leather secured to said ring adjacent the inner end thereof, whereby the fluid pressure is utilized conjointly with said spring for positively maintaining the sealing ring in abutment with said valve.

16. The combination in a pneumatic displacement pump having a valve controlled fluid pressure port provided with an annular recess concentrically disposed in spaced relation thereto, of a fluid pressure sealing ring having an exteriorly reduced inner terminal, a compression spring for said sealing ring, a cup leather fixedly secured to said reduced inner terminal, whereby the fluid pressure is utilized conjointly with said spring for positively maintaining the sealing ring in abutment with said valve.

In testimony whereof I affix my signature.

LOUIS P. MONTANEY.
